UNITED STATES PATENT OFFICE.

WARREN MCARTHUR, OF CHICAGO, ILLINOIS, ASSIGNOR TO THE STEAM GAUGE AND LANTERN COMPANY, OF SYRACUSE, AND THE R. E. DIETZ COMPANY, OF NEW YORK, N. Y.

TUBULAR LANTERN.

SPECIFICATION forming part of Letters Patent No. 445,187, dated January 27, 1891.

Application filed March 22, 1890. Serial No. 344,960. (No model.)

To all whom it may concern:

Be it known that I, WARREN MCARTHUR, a citizen of the United States, residing at Chicago, in the county of Cook and State of Illinois, have invented a new and useful Improvement in Tubular Lanterns, of which the following is a specification.

This invention relates to an improvement in that class of tubular lanterns which are provided with a globe-frame capable of being moved up and down in the tubular frame by means of a lever, which is pivoted to the base of the lantern-frame and attached with its inner arm to the lower part of the globe-frame, so that upon depressing the outer arm of the lever the lower part of the globe-frame will swing upwardly and rearwardly from the burner.

The object of my invention is to provide simple means for locking the globe-frame down in its normal position upon the burner.

In the accompanying drawings, consisting of two sheets, Figure 1 represents a rear elevation of a tubular lantern provided with my improvements. Fig. 2 is a side elevation thereof, partly in section. Fig. 3 is a horizontal section in line $x-x$, Fig. 1. Fig. 4 is a side elevation, partly in section, showing the globe and its support tilted. Fig. 5 is a similar elevation showing the globe-frame lifted from the burner. Fig. 6 is a similar elevation showing a modified construction of my invention.

Like letters of reference refer to like parts in the several figures.

A represents the oil-pot, a the air-chamber secured to the top of the oil-pot, and B the burner surmounting the air-chamber.

C C represent the side tubes secured with their lower branches to the top of the oil-pot and connected with their upper branches to the central depending tube c.

D is the bell or air-gathering plate, mounted on the central tube c so as to be capable of vertical movement thereon.

E represents the lift wires or rods secured with their upper ends to the bell D and attached with their lower ends to the globe-supporting plate e in such manner that the latter can be tilted. This connection is preferably

effected by hooks formed at the lower ends of 50 the lift-wires and eyes formed on the globe-plate.

F represents the globe resting upon the plate e, and G represents the globe-spring, which is attached to the bell and holds the upper 55 end of the globe removably in place. Any other globe-fastening which permits the globe to be released may be employed in place of the globe-spring, if preferred. The bell D, lift-wires E, and plate e form the globe-frame, 60 which is capable of movement up and down in the lantern-frame toward and from the burner.

H represents the lever by which the globe-frame is raised from the burner. This lever 65 is constructed in the form of an inverted-U-shaped frame, and is pivoted to a standard I, which is secured to the oil-pot on the rear side of the lantern. This standard is provided with a horizontal top-bar i, on which the two 70 branches of the lifting-lever turn. The lower branches h of the lifting-lever are arranged horizontally underneath the globe-plate e, and the bow-shaped portion h' of the lever extends upwardly from the standard on the rear side 75 of the globe and forms the rear guard.

J represents the front guard, composed of an inverted-U-shaped frame similar in form to the lifting-lever H, and secured with its lower horizontal portions to the under side of 80 the globe-plate e, so that the latter and the front guard tilt together. The ends of the front guard are provided with eyes j, in which engage outwardly-projecting pivots k, formed on the ends of the lifting-lever, whereby the 85 latter is connected with the globe-supporting plate e.

L represents a spring-catch which is secured to the bell and extends downwardly therefrom to the upper end of the lifting-lever and locks 90 the same in its normal position, in which the globe-frame rests upon the burner. As shown in the drawings, this catch is made of wire and provided near its lower end with a shoulder l, which engages under the bow of the lifting-lever and prevents the upper end of the latter from swinging outwardly, thereby locking 95 the globe-frame in its normal position.

Any other catch which prevents the upper end of the lifting-lever from swinging outward will answer the same purpose—for instance, a hook M connecting the upper end of the lifting-lever with the upper end of the front guard.

I do not claim a guard arranged on one side of the globe and secured to the globe-frame, or a lifting-lever forming a guard on the opposite side of the globe.

I claim as my invention—

1. The combination, with the tubular lantern-frame and the globe-frame capable of moving up and down in the tubular frame, of a lifting-lever pivoted to the base of the tubular frame and having one arm connected with the lower portion of the globe-frame, and a catch attached to the movable globe-frame and engaging with the other arm of the lift-

ing-lever, whereby the lifting-lever is locked to the movable globe-frame, substantially as set forth.

2. The combination, with the tubular lantern-frame provided with a depending central tube, of a bell capable of vertical movement on said tube, a globe-supporting plate, lift-wires connecting said plate with the bell, a lifting-lever pivoted to the base of the tubular frame and having its upper arm projecting upwardly along the globe, and a catch secured to the bell and extending downwardly to the lifting-lever, substantially as set forth.

Witness my hand this 11th day of March, 1890.

WARREN MCARTHUR.
